(57) CLAIM

I claim the ornamental design for a couples massager, as shown and described.

DESCRIPTION

FIG. 1 is a first perspective view of a couples massager.

FIG. 2 is a second perspective view of the couples massager. FIGS. 3 and 4 are left and right side views, respectively, of the couples massager.

FIG. 5 is a top view of the couples massager.

FIG. 6 is a bottom view of the couples massager.

FIG. 7 is a front view of the couples massager; and,

FIG. 8 is a rear view of the couples massager.

The broken lines are directed to environment and are for illustrative purposes only; the broken lines form no part of the claimed design.
